(57) **CLAIM**

The ornamental design for a pneumatic dispensing container, as shown and described.

DESCRIPTION

FIG. 1 is a front-top-right perspective view of a pneumatic dispensing container showing my new design;

FIG. 2 is a rear-top-left perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right-side elevational view thereof; and,

FIG. 8 is a left-side elevational view thereof.

The broken lines in the drawings depict portions of the pneumatic dispensing container that form no part of the claimed design.
